UNITED STATES PATENT OFFICE.

ALFRED M. DUTCHER, OF ST. PAUL, MINNESOTA.

DESIGN FOR A COLLAR-PIN.

59,463.

Specification for Design.

Patented Oct. 25, 1921.

Application filed May 26, 1920. Serial No. 384,474. Term of patent 3½ years.

To all whom it may concern:

Be it known that I, ALFRED M. DUTCHER, a citizen of the United States, residing at St. Paul, county of Ramsey, and State of Minnesota, have invented a new, original, and ornamental Design for a Collar-Pin, of which the following is a specification, reference being had to the accompanying drawings, forming part thereof.

Figure 1 is a side elevation of the collar pin.

Fig. 2 is a plan view of the same.

Fig. 3 is a section on the line 3—3 of Fig. 2.

The drawings illustrate my ornamental pin having a central portion 3 and end portions 2.

The ends 2 of the collar pin engage the free or gaping flaps of a collar to draw or hold the same together, while the member 3 is practically concealed when used in connection with a four-in-hand tie.

I claim:

The ornamental design for a collar pin as shown.

ALFRED M. DUTCHER.
